Primary Examiner — Jae Liang*Assistant Examiner* — Samantha Lynne Brodowski(74) *Attorney, Agent, or Firm* — Thompson Coburn LLP(57) **CLAIM**

The ornamental design for a lid as shown and described.

DESCRIPTION

FIG. 1 is a top perspective view of a lid;

FIG. 2 is a bottom perspective view thereof;

FIG. 3 is a top plan view thereof;

FIG. 4 is a bottom plan view thereof;

FIG. 5 is a front elevational view thereof; and,

FIG. 6 is a right-side elevational view thereof.

A rear elevational view is not shown because it is identical to the front elevational view shown in FIG. 5. A left-side elevational view is not shown because it is identical to the right-side elevational view shown in FIG. 6. The broken lines are for the purpose of illustrating environment only and form no part of the claimed design.

1 Claim, 5 Drawing Sheets---
